Attorney.

United States Patent Office.

JOHN A. BAILEY, OF DETROIT, MICHIGAN, ASSIGNOR TO HIMSELF, L. E. WEBB, JOSEPH LEDERLE, ANTHONY LEDERLE, AND JOHN H. WELLS.

Letters Patent No. 105,883, dated August 2, 1870.

IMPROVEMENT IN EXCAVATING-MACHINES.

The Schedule referred to in these Letters Patent and making part of the same.

To all to whom it may concern:

Be it known that I, JOHN A. BAILEY, of Detroit, in the county of Wayne and State of Michigan, have invented a new and improved Excavating-Machine; and I do hereby declare that the following is a full, clear, and exact description thereof, which will enable others skilled in the art to make and use the same, reference being had to the accompanying drawing forming a part of this specification.

This invention relates to improvements in excavating-machines, and consists in a combination with the horizontally-revolving platform, for turning the scoop and its supports and the pivot thereof, of cylinders and pistons, so arranged that the turning may be effected by water or other liquids or air, pumped or otherwise forced into the cylinders and acting on the pistons.

The invention also consists in a combination with the scoop and the pistons and cylinders heretofore used for working the scoop of other pistons and cylinders, arranged to aid in forcing the scoop into the earth, also for turning the scoop on its axis while filling and for discharging it.

The invention also consists in an improved arrangement of tripping and closing apparatus for the bottom of the scoop, made to open and discharge thereat.

Figure 1 represents a side elevation of my improved machine, the dotted lines representing the scoop and operating devices in the elevated position for dumping.

Figure 2 represents a plan view of the same, with the engines, pumps, and pipe-connections to be used, shown in dotted lines.

Similar letters of reference indicate corresponding parts.

A represents the platform for the support of the operating parts. It is mounted on a vertical pivot, B, rising up from and fixed to the axis of a table, C, whereon the platform is to revolve horizontally, as is required for such machines.

E is a wheel on the top of the pivot, and fixed to it.

F represents cylinders fixed on the platform A, and provided with pistons G, behind which, in the cylinders, water or other liquid or air is to be forced through pipes I, shown in dotted lines, to drive the pistons outward.

H is a cord or wire rope, attached at both ends to the platform A, and passing over the projecting ends of the pistons, also around the wheel E, as shown. The cord is adjusted when both pistons are moved back in the cylinders, and made as taut as possible. The outer ends of the pistons are provided with grooved rollers K, for the rope to reduce the friction.

By this arrangement, the water being forced into one cylinder, and moving the piston thereof, will turn

the platform around the pivot in one direction, and, when forced into the other cylinder, will turn it the other way.

The cylinder-pistons and rope are preferably made long enough to turn the platform a whole revolution. Of course the pistons may be connected to the wheel E in various ways to effect the turning, or the turning may be effected by causing the pistons to turn gear-wheels, gearing with the wheel E or with the other gear-wheels attached to the bed C.

L represents cylinders containing pistons, provided with rods for working the scoop M, which is pivoted at N to the cross-head c, attached to the outer ends of the ways q.

I now propose to combine other cylinders, R, with the cylinders L and the scoop, to aid in working the latter, and in this example I attach these cylinders to the ways Q, connecting the pistons to cross-heads S, and connecting the latter to the scoop by articulated links T U.

These cylinders R and pistons are designed to work, in conjunction with the others, L, for forcing the scoop into the ground and turning it up as it fills, which is done by imparting the same speed to the pistons of both cylinders at first, then lessening the speed of the upper ones, which may be done by gauging the water forced in against the pistons.

The scoop may be tilted by moving out the pistons of cylinders R, or by holding them still and moving back the pistons of cylinders L.

When the scoop is emptied, all the pistons are run back together for the next operation.

At A¹ I have represented a water-tank, in dotted lines, for containing the water to be used, into which the water is discharged after using.

A² represents pipes, also in dotted lines, to be used for conducting the water to and from the cylinders. Of course each cylinder must have a supply-pipe connection with the pumps, and an exhaust leading to the water-tank, but they may be arranged in any preferred way.

I propose to make the scoop so as to open at the bottom, for discharging therefrom when required, and therefore suspend the bottom V, which is made separate from the other part, on the arms W, which are pivoted at X, and rising at the upper ends near to the top, where they are engaged, by spring-catches Y, to hold the bottom closed.

The axis of these catches has an arm, Z, attached at one end for the connection of a tripping-cord, by which the catches are disengaged from the arms W to open the scoop and let the contents discharge.

For closing the bottom of the scoop automatically, when the scoop is turned down at the front for taking a load, I arrange a spring-bar, z¹, on the cross-bars z²,

to project downward, so that the bottom of the scoop will strike against it, the bar, and the arms W will be forced under the catches Y.

Having thus described my invention,

What I claim as new, and desire to secure by Letters Patent, is—

1. The combination, with the platform and the pivot whereon it oscillates, of the pistons, which are connected by suitable means, and worked in cylinders by means of water or other fluids, for effecting the oscillation of the platform, substantially in the manner described.

2. The combination, with the cylinders L and their

pistons, of the scoop M and the cylinders R and their pistons, substantially as specified.

3. The combination, with the bottom V of the scoop and arms W, arranged as described, of the holding and tipping-catches Y and spring bar z, substantially as specified.

The above specification of my invention signed by me this 30th day of March, 1870.

JOHN A. BAILEY.
